UNITED STATES PATENT OFFICE.

JAMES YOUNGSON, OF WINSTON-SALEM, NORTH CAROLINA, ASSIGNOR OF ONE-HALF
TO MICHAEL D. GANTT, OF WINSTON-SALEM, NORTH CAROLINA.

BOAT PROPULSION MEANS.

Application filed August 27, 1921. Serial No. 495,857.

To all whom it may concern:

Be it known that I, JAMES YOUNGSON, a citizen of the United States, residing at Winston-Salem, in the county of Forsyth 5 and State of North Carolina, have invented certain new and useful Improvements in Boat Propulsion Means, of which the following is a specification.

This invention relates to boat propulsion means and has for an object the provision of water wheels operated in conjunction with endless paddles to obtain a maximum impelling force which enables the boat to attain a greater velocity in the water.

Another object of the invention is to provide endless propulsion means, which, when traveling with the trend of the current will require only a minimum amount of motive energy to operate the boat.

A further object of the invention is to protect the propulsion means by encasing the latter within suitable walls to prevent contact of extraneous materials with said means, the walls being perforate to permit free passage of water therethrough.

The above and other objects of this invention will be in part described and in part understood from the following description of the present preferred embodiment of the 30 invention taken in connection with the accompanying drawings wherein:—

Fig. 1 is a top plan view of a boat showing a portion thereof removed to disclose propulsion means constructed in accordance 35 with this invention; and

Fig. 2 is a longitudinal sectional view taken on the line 2—2 of Fig. 1 looking in the directions of the arrows.

In the drawings a boat 3 is shown which 40 may be of any desired size and configuration and made of any materials. Moreover the boat may be equipped with the usual or any desired type of steering means.

Propulsion means constructed in accordance 45 with this invention consists especially of two or more series of endless paddle chains, each series comprising a pair of sprocket chains 4 which engage sprocket wheels 5 carried by driven shafts 6. By 50 preference each series of paddle chains is mounted in close proximity to the side walls of the boat as shown in Fig. 1. Each pair of chains 4 has mounted thereon and extended transversely thereacross paddles or blades 7. Each paddle in the present instance is

shown to be of rectangular shape and has one of its lateral margins fixedly secured to the sprocket chains so that the paddles will at all times be at right angles to the chains. The driven shafts 6 may be connected with suitable power means in a manner well known in the art.

Each series of paddle chains is preferably mounted to operate parallel with the longitudinal axis of the boat and the ends thereof terminate short of the ends of the boat. A driven shaft 8 extends transversely through the boat and has the opposite ends thereof arranged midway between the upper and lower runs of the sprocket chains and journaled in the sides of the boat. The shaft 8 has a pair of paddle wheels mounted thereon each of which consists of a hub 9 which has paddles 10 radiating therefrom. The hub 9 has its ends extended slightly beyond the pair of chains through which it passes with its periphery in contact with the inner faces of the chains. Upon reference to Fig. 2 of the drawings it will be noted that upper and lower series of driven shaft 6 and sprocket 75 wheels 5 are provided to retain the sprocket chains in a substantially oblong shape. This will prevent sagging of the chains or binding of the same on the hub 9. Moreover the hub carries peripheral teeth 11 which are engaged by the sprocket chains 4 to produce a positive driving connection between the paddle wheel and sprocket chains. The paddles 10 of each paddle wheel or water wheel project between each pair of sprocket chains 80 and impinge the paddles 7. In this way the driving force of the paddle chains is augmented.

While it is apparent that power may be applied to the shafts 6 and 8 for driving the sprocket chains and water wheel, 95 it is nevertheless to be understood that where the water resistance is not very great, such for instance as when travelling with the trend of the current, power may be transmitted to the driven shaft 8 only causing the water wheels to be rotated and the paddle chains 4 actuated by the movement of the paddle wheels in conjunction with the impact of the water.

In order to protect the propulsion means 105 from extraneous materials, such as débris, fish, or the like, a protective casing comprising a series of perforate walls 11' is provided. These walls may be made of a reticular material so as to permit influx of 110

water therethrough for engagement with the paddles 7 and 10. As shown in the drawings preferably bottom, end and side walls are provided to completely encase the propulsion means.

In use of this device it is assumed that the normal water level will be slightly below the axis of the shaft 8 or at least not above said shaft. When power is applied to the shafts 6 and 8 the paddle wheel and paddle chains will be operated to impinge the water and propel the boat in an apparent manner. Of course the driven shafts may be associated with suitable differential mechanism to permit the propulsion means to be reversed when so desired. It is apparent that various changes may be made in this device, especially in the details of construction, proportion and arrangement of parts without departing from the spirit and scope of the appended claims.

What is claimed is:—

1. Boat propulsion means including chains equipped with paddles, water wheels cooperative with said chains, and perforate means 25 to encase said chains and paddle wheels substantially as described.

2. Boat propulsion means including chains equipped with paddles, paddle wheels cooperative with the chains, said chains and paddle wheels being arranged adjacent the sides of the boat, and perforate walls arranged beneath said paddle wheels and paddle chains and extending upwardly at the sides thereof, in parallelism with the sides of the 35 boat to encase said wheels and chains.

In testimony whereof I affix my signature in presence of two witnesses.

JAMES YOUNGSON.
